UNITED STATES PATENT OFFICE.

EDWARD F. JONES, OF BINGHAMTON, NEW YORK.

DESIGN FOR A STANDARD OR BASE FOR SCALES.

SPECIFICATION forming part of Design No. 24,479, dated July 16, 1895.

Application filed June 11, 1895. Serial No. 552,484. Term of patent 3½ years.

To all whom it may concern:

Be it known that I, EDWARD F. JONES, of Binghamton, in the county of Broome and State of New York, have invented a new and original Design for a Standard or Base for Weighing-Scales, of which the following is a full, clear, and exact description.

Reference is to be had to the accompanying drawing, forming a part of this specification, in which the figure represents in perspective a standard and base embodying my new design.

The leading feature of my design consists in a standard having a stem projecting laterally from its base, said stem terminating in

a plurality of arms representing modified clover-leaves

A minor feature of the design is the configuration of the upper end of the standard, the same presenting an ear *a* and two upwardly-curved diverging arms *b b*, each having a lateral eye, one of said eyes having an opening *c* leading therefrom.

I claim—

The design for a standard and base for weighing scales, herein shown and described.

EDWARD F. JONES.
